(57) **CLAIM**

We claim an ornamental design for an near field communication (NFC) to USB/Bluetooth loyalty reader for mobile and NFC tags, substantially as shown and described.

DESCRIPTION

FIG. 1 is a bottom perspective view for the device.

FIG. 2 is a bottom view for the device.

FIG. 3 is a top view for the device.

FIG. 4 is a left view for the device.

FIG. 5 is a right view for the device.

FIG. 6 is a rear view for the device; and,

FIG. 7 is a front view for the device.

Any broken lines depicted represent the bounds of the claimed design. All other broken lines are superimposed on continuous surfaces and are for illustrative purposes only; the broken lines form no part of the claimed design.

The article is not limited to the scale shown herein. As indicated in the tile, the article of manufacture to which the ornamental design has been applied is an near field communication (NFC) to USB/Bluetooth loyalty reader for mobile and NFC tags.
